UNITED STATES PATENT OFFICE.

HARRY DINHOFER, OF NEW YORK, N. Y.

WATCHCASE.

Application filed December 16, 1927. Serial No. 240,366.

This invention relates to an improvement in watch cases of the wrist watch type and has for its object to provide a case so constructed that the various parts which go to make up the case shall have movement with respect to one another whereby the case may readily conform itself to the curvature of the wrist and may be worn comfortably at all times.

At the present time, the wrist watches of certain types are made in elongated form so that certain parts of the same are likely to protrude beyond the sides of the wrist and render the case awkward in appearance as well as causing it to improperly fit the wrist curvature.

The object of my invention therefore, is to hinge certain protruding parts of the case, particularly the strap-receiving parts, with respect to the body of the case so that these parts may incline and follow the curvature of the wrist.

With these objects and such other objects as may hereinafter appear in view, I have devised the particular arrangement of parts hereinafter set forth and more particularly pointed out in the claims appended hereto.

Referring to the accompanying drawing,

Figure 1 is a plan view of a watch case made in accordance with my invention;

Figure 2 is a side elevation of the same;

Figure 3 is a plan view of one of the strap-receiving members prior to the installation therein of the hinge member;

Figure 4 is a sectional view on the line 4—4 of Figure 3;

Figure 5 is a plan view of the hinge member;

Figure 6 is a sectional view on the line 6—6 of Figure 5;

Figure 7 is a plan view of the cover plate for the member shown in Figure 3; and

Figure 8 is a sectional view on the line 8—8 of Figure 1.

Throughout the various views of the drawings, similar reference characters designate similar parts.

In the embodiment of my invention disclosed in the accompanying drawing, 1 indicates the body of the watch case which may be of any desired shape and is provided with a beveled or inclined marginal edge portion 2. Located at a slight distance from the opposite edges 3 and 4 of the case are shown the wrist-strap-receiving members 5 and 6. Each of these members 5 and 6 are similar in construction so a description of one will suffice.

Each of said members is composed of a hollow trough-shaped casing 7 which is provided with a longitudinal part 8. This part 8 is provided with an outer upstanding flange 9^a 60 and an inner shorter but higher flange 10. The part 8 is provided with a pair of laterally extending projections 9 each of which is enclosed by side flanges 10. These parts 9 are connected by a cross-bar 11 which receives the wrist strap or ribbon 12. If desired, the cross-bar 11 may be made removable to facilitate the attachment of the wrist strap 12.

At 13 is shown a hinge member which consists of a pair of spaced strips 14 having 70 one of their ends curled or bent downwardly as at 15, the inner terminations of said curled parts 15 being connected by an integrally formed cross-bar 16.

The two parts 7 and 13 just described comprise the two main elements of the strap-receiving member and the hinge therefor and these two parts are connected as follows. The part 13 is placed in position within the trough-like member 17 by positioning the 80 cross-bar 16 in the elongated channel member 8, the two parts 14 protruding out of the cut-out sections 17 located at the ends of the up-standing flange 10. Thereupon the upstanding flange 10 is rolled or curled over the bar 85

16 so that it encloses the same and retains the bar within the casing 7. As is shown in Figure 8, this curling or bending over of the flange 10 is so performed that the member 13 is freely movable or is in other words, 90 hinged to the part 7. Thereupon, a closure plate 18 is placed over the top of the trough-shaped member 7. This plate 18 conforms in shape to the entire member 7, in that it is provided with laterally extending ends 19 and 95 is also provided with cut-away parts 20. These parts 20 are lined with the cut-out parts 17 located in the trough-shaped casing 7 so that the strips 14 may protrude and are 100 freely movable without interference by the cover plate. The cover plate is soldered in position and when this is done, the hinge member 13 has the bar 16 completely enclosed and the wrist-strap-receiving member presents the appearance disclosed in Figures 1 105 and 2. Thereupon the strips 14 are soldered or otherwise fixed to the inclined upper marginal face 2 of the watch case 1.

Through the hinge arrangement disclosed, it will be seen that the strap-receiving members 5 and 6 are freely pivotal to a considerable extent in a downward direction, allow-

ing them to closely conform to the curvature of the watch and permitting a wrist watch to be made in an elongated form without presenting an awkward appearance when worn.

Having described one embodiment of my invention, it is obvious that the same is not to be restricted thereto, but is broad enough to cover all structures coming within the scope of the annexed claims.

10. What I claim is:—

1. A watch case, a pair of spaced strips secured thereto and projecting from said case, a bar connecting said strips, a wrist-strap receiving casing having a hollow part in which said bar is located, a flange on said casing bent over and enclosing the bar, and a cover plate secured over the bent-over flange and the bar.

2. A watch case having a separate wrist-strap-receiving hollow end casing, said separate end casing containing a bar, a flange on said end casing bent over said bar, and several projections integrally formed on said bar, said projections extending out of the

end casing and secured to the body of the 25 watch case.

3. A watch case having an end casing, said casing comprising a hollow box-like section extending co-extensively with the end of the watch case and slightly spaced therefrom, 30 several connecting strips extending between the end casing and the case, said connecting strips having a connecting cross-bar located and confined within the end case, and a curled over flange on said end case for confining the 35 cross bar.

4. In a watch case construction, a wrist-strap holding member comprising a hollow elongated casing having laterally projecting ends, a strap-receiving bar extending between and connecting said ends, a bar pivotally held within the casing by a bent over flange thereon, openings in said casing, and strips on 40 said bar extending out of said openings and secured to the watch case.

Signed at the city, county and State of New York, this 15th day of December, 1927.

45 HARRY DINHOFER.
